UNITED STATES PATENT OFFICE.

WILLIAM S. MENDEN, OF BROOKLYN, NEW YORK, ASSIGNOR TO MEGOSIN COMPANY, INC., A CORPORATION OF NEW YORK.

SPEED-CONTROL DEVICE FOR VEHICLES.

1,137,882.

Specification of Letters Patent.

Patented May 4, 1915.

Application filed July 3, 1913. Serial No. 777,238.

To all whom it may concern:

Be it known that I, WILLIAM S. MENDEN, a citizen of the United States, residing in the borough of Brooklyn, county of Kings, 5 and State of New York, have invented certain new and useful Improvements in Speed- Control Devices for Vehicles, of which the following is a full and clear specification.

This invention relates to speed control devices for vehicles of various descriptions and is especially applicable to public conveyances such as rapid transit cars which are operated at relatively high speed through some portions of their route but which along 15 other portions of their route may be restricted to slow speeds.

In the modern development of rapid transit systems, it has become of the utmost importance that the speed of cars be 20 limited in order to avoid accidents of various descriptions.

The primary object of the present invention is to provide improved mechanism for rendering it impossible for the car operator 25 to run above a definite limit and contemplates suitable provision for varying this limit to meet the varying requirements of different zones of travel over which the vehicle passes.

30 The specific features of my invention will appear in the specification and be pointed out in the appended claims, reference being had to the accompanying drawings, in which my invention is exemplified in an adaptation 35 to a rapid transit car.

In the drawings, Figure 1 is a wiring diagram of an electrically operated embodiment of my invention; Fig. 2 is a similar diagram of a modification; Fig. 3 is a diagram of another modification; Fig. 4 is a side elevation of a circuit closing plunger and trip mechanism therefor; Fig. 5 is an end elevation of the same.

Referring first to Fig. 1 of the drawings, 45 the general outline of one embodiment of my invention will be understood. The axle 1 carried by wheels 2 (only one of said wheels being shown in dotted lines), constitutes a member which rotates continuously 50 while the car is in motion. Adjacent to the axle 1 is mounted an auxiliary source of power such as a dynamo, comprising the armature 3 and a field winding 4 connected in series therewith by a line 5. In order to provide suitable means for periodically driving

the armature 3, a roller 6 is journaled at 7 in a swinging bracket 8, which carries at its outer end an electromagnet 9 which is energized at predetermined times and intervals by means of a line wire 10 which 60 branches from the main circuit at any suitable point, (not indicated on the drawings). A line 11 connects the magnet 9 with a contact 12 and is adapted to be grounded through the switch bar or contact 13 which 65 is grounded through a line 14 as indicated. Whenever the plunger 35 is elevated by a cam track 37 which happens every time a car enters a zone within which an automatically controlled speed limit is maintained, 70 the contact 13 engages the contact bar 12 and an energizing current passes through wire 10, magnet 9, wire 11, contacts 12 and 13 and ground line 14. The pivot 15 of the bracket 8 is coaxial with the armature 3 of 75 the auxiliary dynamo, so that the contact roller 6 is adapted to be sprung into and out of rolling contact with the axle 1 when the magnet 9 is energized. The main branch of the circuit energized by the generator 3 is a 8 line wire 16, which leads to a solenoid 17 surrounding a reciprocable core 18, as shown to the left in Fig. 1. Projecting upwardly from the core 18 is a rod 19 which carries a cross bar or contact 20 at its upper end. 85 The contact 20 is adapted to bridge the spaced contacts 21 and thereby to close a gap in the main control circuit of which the lead wires 22 constitute a part. Depending from the core 18 is another rod 23 which 90 carries at its lower end a valve 24 which is adapted under certain conditions, to be hereinafter pointed out, to open and close the chamber 25 which is in open communication with a pipe 26, forming part of the automatic air brake mechanism. Solenoid 17 is connected by a line wire 27 with a graded resistance element 28. In order to permit of different degrees of resistance being thrown into the solenoid operating circuit, a 95 plurality of branches 29, 30 and 31 are connected at suitable points in the resistance 28. Said branches terminate in fixed contacts 32, 33 and 34, which may be closed successively by the contact bar 13, when it is 100 elevated in the manner to be presently explained. A plunger 35 which carries the contact bar 13 control has in the preferred embodiment of my invention, a roller 36 journaled in the lower end thereof, which 110

2

roller is adapted to coöperate with cam tracks 37, which may be located at any desired points along the route of the car or vehicle. Said cam tracks 37 may be of any suitable height corresponding to the required elevation to be imparted to the plunger 35 in closing the solenoid operating circuit through any one of the resistance branches 29, 30 and 31. A stop or post 38 may be employed in the preferred embodiment of my invention for releasing the plunger 35 at the end of any zone or period of travel for which a given limit to the speed of the car has been decided upon. The preferred construction of the plunger together with the circuit closing device and operating mechanism connected therewith will be understood from an inspection of Figs. 4 and 5. Thus the plunger 35 is reciprocably mounted in the spaced arms of a yoke 39, which may form a rigid projection from an inclined member 40 (see Fig. 4) of the frame work of a car. Rigidly mounted on the plunger 35 is a collar 41 which serves to limit the downward movement of the plunger 35 under the action of a compression spring 42 which is mounted around the plunger 35 and intermediately of the collar 41 and the upper arm of the yoke 39.

30 Simple and efficient means for releasably holding the plunger 35 in any one of the positions to which it is elevated, may be provided by the following construction. On a pin 43 which is rigid with the yoke 39, is journaled the hub 44 of a pendulum or trigger 45. The upper arm of said trigger carries a plurality of laterally projecting lugs 46, which are separately adapted to engage a toe 47 of a dog 48, said dog being pivoted at 49 on a bracket arm 50 which projects laterally from the upper end of the plunger 35. A lateral projection 51 on the upper end of the dog 48 is adapted to abut against the upper end of the plunger 35 and 45 to retain the dog against a clockwise displacement after the plunger has been raised. Any suitable means such as the compression spring 52 may be employed to yieldingly retain the dog 48 in the position shown in

50 Fig. 5. Thus as the plunger 35 is raised the toe 47 will drag over the lugs 46 until the required elevation is attained. As shown in Fig. 4, the lugs 46 on the upper end of the trigger 45, are arcuately curved with respect to the pin 43 as a center. A torsion member such as the spring 53 has one end connected to the trigger 45 and the other end to the yoke 39, and is suitably tensioned to normally retain the trigger 45 in vertical position. When, however, the progress of the car brings the trigger 45 into engagement with the post or stop 38, said trigger is displaced as indicated in dotted lines in Fig. 4, and the toe 47 being released, 60 the plunger 35 is permitted to drop into circuit

70 circuit breaking position. A tension spring 54 serves to return the core 18 to normal position, shown in Fig. 1, when the circuit is broken. The armature 3 of the dynamo is grounded at G.

75 As shown in Fig. 2 of the drawings, the present invention can be embodied on a vehicle which embodies simply a braking mechanism and for this purpose can be operative independent of the main driving circuit of a vehicle such as a trolley car. Thus, as shown in Fig. 2, the leads 22, contacts 21 and contact bar 20 with its supporting rod 19 can be omitted. In this embodiment, it will be sufficient to have a yielding support such as the spring 55 which may be secured at its lower end to the plunger or core 18' and at its upper end to a fixed support 56.

80 In Fig. 3 is shown an embodiment of the invention in which the main circuit is controlled. Thus, the leads 22 with their contacts 21 are embodied along with the bridging contact 20 on the upper end of the rod 19 which is carried by the core 18 of the solenoid 17.

85 In most rapid transit systems whether for the transportation of freight, passengers or whatever purpose, there are zones of travel or localities in which the speed of a vehicle 95 should be restricted to a definite maximum limit. Thus on busy thoroughfares, at junctions both underground and surface, in transition connections between surface and elevated lines or underground with surface or elevated or other places in which long steep grades may be required, some positive means should be employed to prevent the speed limit being exceeded. Referring to Fig. 1, at the beginning of each limited 100 zone of travel, suitable plunger-actuating means such as the cam bar 37, is disposed adjacent the path of the vehicle. When the plunger rises, according to Fig. 1, as soon as the contact 13 bridges the gap between 105 one of the fixed contacts 32, 33 or 34 and the plate 12, current from the feed wire 10, energizes the magnet 9, through a circuit including wire 11, contacts 12, 13, plunger 35, and wire 14 to ground G. Immediately the 110 magnet 9 is thrown toward the axle 1 until contact wheel 6 engages axle 1 upon which the generator 3 is caused to generate an electro-motive force which varies with the speed of the axle 1. It will be seen that according to which of the branches 29, 30 or 31 is connected up in circuit with the solenoid 17, the voltage necessary to operate solenoid 17 will be low, medium or high. 115 In consequence, if the current passes over the lowermost branch 31 and the entire resistance 28, the core 18 will not be shifted until the speed of the vehicle becomes high enough to produce the required voltage for 120 imparting the required energization to the 125 130

solenoid 17 through the resistance 28. When, therefore, the speed of the car reaches the speed limit, the main operating circuit is broken, or the brakes thrown in action, 5 or both of these results occur, depending upon the particular embodiment. Under these conditions, the current from the dynamo 3, traverses wire 16, solenoid 17, wire 27, resistance 28 branch 31 (or 30 or 29), 10 ground G, G', and dynamo 3. It will be seen therefore that whenever the speed limit is exceeded, the vehicle automatically comes under the control of mechanism over which the operator of the vehicle has no control.

15 What I claim is:

1. In a vehicle, the combination with a speed controlling instrumentality, of a source of power which varies with the speed of said vehicle, a circuit including said power source and instrumentality, said instrumentality being adapted under a fixed amount of resistance in said circuit to become operative under a predetermined speed of the vehicle, and means for predetermining the resistance in said circuit to vary the speed limits at which said instrumentality becomes operative.
2. In a vehicle, the combination with a speed controlling instrumentality, of a source of power which varies with the speed of said vehicle, a circuit including said power source and instrumentality, said instrumentality being adapted under a fixed amount of resistance in said circuit to become operative under a predetermined speed of the vehicle, and means for varying the resistance in said circuit to vary the speed limits at which said instrumentality becomes operative, said means including graded resistance, and a plunger suitably mounted on said vehicle to be displaced by means disposed along the route of said vehicle.
3. In a vehicle, the combination with a speed controlling instrumentality, of a source of power which varies with the speed of said vehicle, a circuit including said power source and instrumentality, said instrumentality being adapted under a fixed amount of resistance in said circuit to become operative under a predetermined speed of the vehicle, and means for varying the resistance in said circuit to vary the speed limits at which said instrumentality becomes operative, said means including graded resistance, and a plunger suitably mounted on said vehicle to be displaced by means disposed along the route of said vehicle, said plunger being adapted to make and break the circuit through different amounts of 50 said resistance at different predetermined points.
4. In a vehicle, the combination with a speed controlling instrumentality, of a sole-

sistances, and means acting at a fixed point of travel for connecting a predetermined amount of said resistances in circuit with said electrical source and solenoid, said means automatically predetermining the speed limit at which the speed controlling instrumentality becomes operative.

5. In a vehicle, the combination with a speed controlling instrumentality, an energizing circuit therefor, means for varying the resistance in said circuit to regulate the current flowing through said circuit, and automatic means acting at a fixed point of travel of said vehicle, for positioning said resistance varying means to predetermine the speed limit of said vehicle.

6. The combination with a vehicle, of means for controlling the speed of said vehicle, said controlling means being adapted to limit the speed of the vehicle to any one of a plurality of speeds, an element capable of various degrees of displacement, operably connected to said controlling means, and means for automatically locking said element in displaced position, said locking means being released automatically at the end of a zone of travel in which the speed is to be limited.

7. In a vehicle, the combination with a speed controlling instrumentality, an operating solenoid adapted to be operated by currents of different strengths depending upon the amount of resistance in circuit therewith, a plurality of resistances, adapted to be thrown into circuit with said solenoid, an energizing circuit for said solenoid including one or more of said resistances and means adapted to be operated at predetermined points in the travel of said vehicle, for determining the amount of resistance in the energizing circuit.

8. In a vehicle, the combination with a speed controlling instrumentality, an operating solenoid therefor adapted to be operated by currents of different strengths depending upon the amount of resistance in circuit therewith, a resistance adapted to be thrown into circuit with said solenoid in greater or less amount, an energizing circuit for said solenoid including more or less of said resistance, and means adapted to be operated at predetermined points for determining the amount of resistance in the energizing circuit, said means including a series of contacts respectively, connected to different parts of the resistance and a member through which the energizing circuit is completed which member is adapted to be displaced in a greater or less degree by co-operating members disposed along the route of said vehicle.

9. In a vehicle, the combination with a speed controlling instrumentality, of a sole-

- 4
- of contacts by means of which different amounts of said resistance can be included in a circuit for energizing said solenoid, an energizing circuit including a movable contact adapted to successively engage the first mentioned contacts, a displaceable member carried by said vehicle and adapted to displace said movable contact and means disposed along the route of said vehicle for imparting different amounts of displacement to said member to determine the amount of resistance in circuit with said solenoid, the speed limit at which said instrumentality becomes operative being different for different amounts of resistance.
10. In a vehicle, the combination with a speed controlling device, an electrical operating circuit therefor, resistance, a series of contacts suitably connected to include different amounts of said resistance, a member suitably mounted to make and break the circuit through said contacts singly, and means disposed along the route of said vehicle to displace said member a predetermined amount to automatically predetermine the sensitiveness of said speed controlling device.
15. In a vehicle, the combination with a speed controlling instrumentality, of a solenoid for actuating the same, a resistance electrically connected to said solenoid, a plurality of branch wires leading from different points of said resistance, said branch wires being provided with contacts, a plunger adapted to successively contact with said contacts, and means disposed along the route of said vehicle for displacing said plunger to selectively engage one of said contacts, said solenoid and plunger being connected up in an energizing circuit which is thus completed.
20. The combination of a vehicle, a speed control instrumentality, a magnetic coil for controlling the same, a source of power which varies with the speed of said vehicle, resistance means provided with a plurality of branches for varying the amount of resistance in circuit, a plunger reciprocably mounted to adapt it to close a circuit through any one of said branches, a circuit including said source, coil, resistance and plunger, and means for releasably holding said plunger in any position to which it may be displaced.
25. The combination of a vehicle, a speed control instrumentality, a magnetic coil for controlling the same, a source of power which varies with the speed of said vehicle, resistance means provided with a plurality of branches for varying the amount of resistance in circuit, a plunger reciprocably mounted to adapt it to close a circuit through any one of said branches, a circuit including said source, coil, resistance and plunger, and means for releasably holding said plunger in any position to which it may be displaced, said holding means comprising a trigger having spaced lugs projecting therefrom and a dog carried by said plunger.
30. The combination with a vehicle, of a generator adapted to have running contact with a moving part of the propelling mechanism of said vehicle, a speed controlling element, a solenoid for operating the same, a circuit for connecting said element with said solenoid, and means for varying the resistance of said circuit to raise and lower the speed limit at which said solenoid becomes operative upon said speed-controlling element, said means including a series of resistances arranged in parallel, a plunger operatively mounted with respect to said resistances, and means for operating said plunger.
35. The combination with a vehicle, of a generator adapted to have running contact with a moving part of the propelling mechanism of said vehicle, a speed-controlling element, a solenoid for operating the same, a circuit for connecting said element with said solenoid, and means for varying the resistance of said circuit to raise and lower the speed limit at which said solenoid becomes operative upon said speed-controlling element, said means including a series of resistances arranged in parallel, a plunger operatively mounted with respect to said resistances and means for operating said plunger, said plunger-operating means being adapted to operate said plunger to different extents to correspond to the speed limit requirements of different zones of travel.
